United States Patent Office

Des. 228,883
Patented Oct. 30, 1973

228,883

STORAGE CONTAINER

Elmer F. Sanzari, 194 Colonial Court,
Teaneck, N.J. 07666

Filed Mar. 29, 1971, Ser. No. 129,300

Term of patent 14 years

Int. Cl. D9—03

U.S. Cl. D9—199

FIG. 1

FIG. 2

FIG. 3

FIG. 1 is a top, front perspective view of a storage container showing my new design;

FIG. 2 is a rear perspective view with the legs partially retracted; and

FIG. 3 is a front perspective view with the lid closed and the legs partially extended.

I claim:

The ornamental design for a storage container, substantially as shown.
